HARRY L. BROOKS AND THOMAS O'FLYNN, OF MIDDLETOWN, OHIO, ASSIGNEES TO THE BLACK-CLAWSON COMPANY, OF HAMILTON, OHIO, A CORPORATION OF OHIO

PAPER MAKING APPARATUS

Application filed July 10, 1926. Serial No. 121,674.

This invention relates to paper-making apparatus and more particularly to paper-making apparatus of the type in which the paper is pressed or compressed after it is formed, 5 primarily for the purpose of removing excess liquid matter therefrom.

One of the principal objects of the invention is to provide improved apparatus for removing water from newly formed paper.

10 Another object is to provide means for increasing the life of endless felts employed in paper-making machinery and to maintain the desired quality and characteristics of such endless felts.

15 Other and further objects of the invention will appear from the following description taken in connection with the accompanying drawings in which,

Fig. 1 is a diagrammatic view of part of a 20 paper-making machine constructed in accordance with the present invention, the part illustrated being a press part; and

Fig. 2 is a fragmentary view similar to Fig. 1 illustrating a modified form of the invention.

Paper-making machinery commonly comprises a paper-forming part, which may be the well-known cylinder machine or of the Fourdrinier type, for receiving paper stock 30 and forming such stock into a continuous sheet or web of paper. From the delivery end of such paper-forming part or machine the paper passes to what is known as a press part or machine which compresses the newly 35 formed paper to squeeze out surplus water, and the like.

Press parts as heretofore constructed consist of a pair of superposed press rolls, through the nip of which there passes an endless felt which receives the newly formed paper from the paper-making part and carries it through or rather between the press rolls where the paper is compressed. The 40 endless felt is of considerable length and is carried by suitable guide rolls which hold the felt under suitable tension and keep it flat. The endless felt is driven from one of the 45 press rolls which also serves as a driving roll, the driving surface between the endless felt and driving roll being the line of contact at

the nip of the press rolls where the felt passes between them. Owing to the fact that there is but a line contact between the lower press or driving roll and the felt, it is necessary that the felt be placed under sufficient pressure at 55 the nip of the press rolls to secure sufficient friction for driving. With this arrangement there is considerable slippage between the felt and the lower press roll causing the inside or lower surface of the felt to wear 60 rapidly, and likewise there is slippage of the top roll relative to the paper and the felt, which slippage affects adversely the life of the felt as well as the quality of the paper. Also the concentration of the driving strain 65 along the line of the nip results in undue stretching of the felt, a straining or breaking of its fibers, and the closing or distortion of the interstices formed by the fibers in a way that facilitates the imbedding of dirt and grit 70 therein and interferes with the washing or cleaning of the felt. These and other disadvantages growing out of the long existent methods of driving the endless felts of press parts as heretofore constructed greatly limit 75 the life of the felts and interfere with the quality of paper received therefrom.

The present invention contemplates such improvement in the method of driving the endless felt and in the construction and arrangement of the parts generally as to increase the life of the endless felts several times and at the same time improve the quality of the paper received from the press part.

Referring to Fig. 1 of the drawings, 20 80 denotes an endless felt which is adapted to receive a sheet or web of newly formed paper 21 at the front or receiving end of the machine and to carry said paper through the nip 22 of the press rolls 23 and 24 respectively, the 85 press roll 24 being preferably also a driving roll. The felt 20 passes over a guide roll 25 before it passes through the press rolls, and after it has passed through the press rolls it 90 passes over a guide roll 26 which, like the guide roll 25 is positioned in front of or forwardly from the press rolls. The line of approach of the felt is indicated by that portion 95 of the felt designated 27, and the line of de- 100

parture of the felt from the press roll is designated by that portion numbered 28.

After passing over the guide roll 26, the endless felt 20 passes rearwardly over guide 5 rolls 30, 31 and 32 to a stretcher which stretches the endless felt and serves to maintain the same taut. The form of stretcher and its construction is not material to the present invention and is therefore not illustrated. From the stretcher the felt passes 10 forwardly over guide rolls 33, 34, 35 and 36, the guide roll 36 being, in the form of press part here illustrated, at the extreme forward or receiving end thereof.

15 From the foregoing it will be apparent that the endless felt engages the circumferential surface of the driving and press roll 24 over a substantial driving arc of its circumference, the engagement in the form of press part illustrated extending from the nip 22 through approximately 230 degrees to the point of departure at 37 of the felt from the press roll 24. The felt thus having a large surface is frictional engagement with the surface of the 20 driving press roll 24, there is less slippage and wear upon the felt than when the felt simply has a line contact with the driving roll at the nip 22, and the driving of the felt is distributed over an area of the felt of substantial 25 proportions, thus largely relieving the felt of destructive internal strains. The present invention has resulted in increasing the life of the felt several times beyond what was heretofore thought to be the limit of life of such a 30 felt, thus effecting a great saving in the upkeep of the machine. It has the further advantage that the solid matter which is in the liquor that is pressed from the paper, and the foreign matter which comes upon the felt, is 35 not pressed or ground or locked in the interstices of the felt, and the cleaning of the felt may thus be done less frequently than heretofore and with greater ease. The felt retains 40 its original desirable porosity and openness of 45 texture, and result in a better quality of paper.

In the angle between the line of approach of the felt and the line of departure of the felt from the press roll 24, there is disposed suitable means for collecting and carrying off the liquor which flows downwardly from the nip 22 in a direction opposite to the direction of rotation of the lower press roll. Such means for collecting the liquor may comprise a 50 trough 40 having a flexible or other suitable form of doctor 41 bearing upon the surface of the lower press roll and adapted to intercept the liquor flowing downwardly thereon. The liquor collected by the trough 40 may be 55 carried off in any suitable manner as by means of a conduit illustrated at 42.

Owing to the fact that the felt 20 departs from the press roll 24 in a forward direction, means is provided for taking the paper from 60 the felt before the felt leaves the surface

of the press roll, and the next succeeding part of the paper-making machine is preferably extended forwardly to a point not too far removed from the press rolls so as to receive the paper 21 as it comes from the felt 20. 70 The next succeeding part of the paper-making machine is herein illustrated as a second press part having an endless felt 50 which passes forwardly over guide rolls 51, 52, and 53, thence passing rearwardly over guide roll 75 54. The guide roll 53 is disposed near the press rolls 23 and 24, and thus carries the felt 50 of the second press part to a point near the press rolls to take the paper therefrom and to carry it to the next succeeding set of 80 press rolls. It will be observed that the second felt 50 overlies part of the felt 20 of the first press part.

In Fig. 2 there is illustrated a modified form of liquor-collecting means. In this 85 form of the invention there is a roll 60 having a surface of rubber or other flexible material which rolls against the surface of the press roll 24 so as to intercept any liquor flowing downwardly from the nip 22 causing the 90 same to flow towards the ends of the press roll where it is collected and carried off by suitable means not here illustrated. The roll 60 is guided in a suitable slide bearing 61, and in order to maintain sufficient compression 95 between the roll 60 and the press roll 24 there may be provided a pressure roll 62 which is also carried in the slide bearing 61 and the weight of which is adapted to press the roll 60 against the pressure roll 24. 100

While the forms of apparatus herein described constitute preferred embodiments of the invention, it is to be understood that the invention is not limited to these precise forms of apparatus, and that changes may be made therein without departing from the scope of the invention which is defined in the appended claims. 105

What is claimed is:

1. Paper-making apparatus of the character described comprising a positively driven press roll, an endless felt having engagement with the surface of said roll over a substantial arc of its circumference and adapted to be driven thereby, the felt approaching the press roll from the front and also departing therefrom towards the front, guide rolls engaging said departing felt and thereafter carrying it to the rear side of said press roll, and additional guide rolls for then leading said felt forwardly and to the front of said press roll to pass again in engagement with said press roll. 110

2. Paper-making apparatus of the character described comprising a driving press roll, an endless felt having engagement with the surface of said roll over a substantial arc of its circumference and adapted to be driven thereby, the felt approaching the driving press roll from the front and also de- 115 120 125 130

parting therefrom towards the front, guide rolls engaging said departing felt and thereafter carrying it to the rear side of said press roll, and means for taking the paper from said felt before said felt has departed from the surface of said driving press roll, said means comprising a felt overlying the rearwardly carried part of said first-mentioned felt.

10 3. Paper-making apparatus of the character described comprising an upper press roll, a lower press roll, and a doctor comprising roller means in direct frictional engagement with the surface of said lower press roll and driven thereby for removing the liquor running down the surface thereof from the nip of said press rolls.

4. In paper-making apparatus of the character described, comprising a papermaker's felt of substantial length for conveying a wet web from a previous paper-making part, and having a plurality of guide rolls and a tensioning means for said felt; a wet press including upper and lower press rolls having imperforate cooperating surfaces and adapted to exert heavy pressure at the nip thereof, said lower press roll being positively driven, said felt passing from the front through the nip of said press rolls and having direct engagement with the surface of said positively driven lower press roll over an arc of its circumference of substantially 180° or more and adapted to be driven thereby to eliminate objectionable slippage between said felt and said lower driving press roll, said felt serving to convey on its upper surface the wet web formed at a previous paper-making part through the nip of said press rolls to the rear thereof, the felt then returning around the surface of said lower press roll to the front side thereof, and a second felt positioned closely adjacent the rear of said press rolls and felt for receiving the pressed web from said first mentioned felt shortly after the web has passed through the nip of said press rolls and before the corresponding portion of said first mentioned felt has departed from the surface of said lower driving press roll.

5. Paper-making apparatus of the character described, comprising a wet press including upper and lower press rolls adapted to exert heavy pressure at the nip thereof, said lower press roll being positively driven, a papermaker's felt for conveying a wet web from a previous paper-making part, a guide roll on the front side of said press for leading said felt into the nip of said press rolls from the front thereof, said felt then passing from the nip around said positively driven lower press roll in direct engagement therewith over an arc of the circumference of said roll of substantially 180° or more and adapted to be driven thereby, a second guide roll on the front side of said press for receiving

said felt passing from the surface of said positively driven press roll, additional guiding rolls and tensioning means for said felt, and means on the front side of said press and contacting with the exposed surface of said positively driven lower press roll between the lines of approach and departure of said felt for removing liquid from the surface of said press roll.

6. In paper-making apparatus of the character described, comprising a papermaker's felt of substantial length for conveying a wet web from a previous paper making part, and a wet press including upper and lower press rolls adapted to exert heavy pressure at the nip thereof, said lower press roll being positively driven; a guide roll on the front side of said press rolls for directing said felt from the front side of said press rolls through the nip thereof, a guide roll also on the front side of said press rolls for receiving and directing the said felt as it departs from the surface of said lower press roll on the front side thereof, said felt having direct engagement with the surface of said positively driven lower press roll over an arc of its circumference of substantially 180° or more and adapted to be driven thereby to eliminate objectionable slippage between said felt and said lower driving press roll, said felt serving to convey on its upper surface the wet web formed at a previous paper making part through the nip of said press rolls to the rear thereof, the pressed web then being removed from the felt which passes around the surface of said lower press roll and departs therefrom toward the front to be received by said second mentioned guide roll, additional guide rolls receiving said felt from the said second mentioned guide roll and carrying it to the rear side of said press rolls, and a second felt positioned adjacent the rear side of said press rolls and in vertical alignment with a part of the rearwardly carried portion of the first mentioned felt for receiving the pressed web from said first mentioned felt shortly after the web has passed through the nip of said press rolls.

In testimony whereof we hereto affix our signatures.
